UNITED STATES PATENT OFFICE.

HEINRICH J. FREYN, OF CHICAGO, ILLINOIS, ASSIGNOR, BY MESNE ASSIGNMENTS, TO
FREYN AND COMPANY, OF CHICAGO, ILLINOIS, A CORPORATION OF MAINE.

GAS-BURNER.

1,282,802.

Specification of Letters Patent. Patented Oct. 29, 1918.

Application filed December 26, 1916. Serial No. 138,882.

To all whom it may concern:

Be it known that I, HEINRICH J. FREYN, a citizen of the United States, residing at Chicago, in the county of Cook and State of Illinois, have invented certain new and useful Improvements in Gas-Burners, of which the following is a specification.

My invention relates to gas burners, and refers particularly, although not exclusively, to gas burners of relatively large size used for burning blast furnace gas, coke oven gas, and the like, where such gas is utilized for the heating of boilers, blast furnace stoves, or for other similar purposes.

My present invention constitutes an improvement upon the construction of gas burners shown in my Letters Patent No. 1,283,461, granted July 17, 1917. In the said prior construction the burner is designed particularly to be operated in connection with compressed air or other fluid which is preferably introduced through a suitable pipe into an auxiliary air inlet tube, from which it passes into a main air inlet tube which extends into the main casing of the burner, which, in turn, is provided with a gas inlet. The compressed air or other fluid by its aspirating action serves to draw additional air into the auxiliary and main air inlet tubes, this air finally coming in contact with the gas and being longitudinally mixed therewith in a mixing chamber.

It is one of the objects of my present invention to improve the aspirating effect of the air or other fluid which is introduced into the main air inlet tube, and I have found that this result may be accomplished by providing this tube with a constriction resembling that of the well-known Venturi tube.

It frequently happens that under certain conditions it is desirable to operate a gas burner with compressed air or other fluid of comparatively high pressure, under other conditions to operate it with air introduced under slight pressure, as, for example, by a fan blower or the like, while under still other conditions the inducing effect of the gas itself is sufficient to draw into the

burner the proper amount of air to form 50 the desired mixture of gas and air.

It is a further object of my invention to construct my improved burner so that by a simple and inexpensive interchange of the parts carried by the main air inlet tube 55 the burner may be adapted to operate under the various conditions just outlined.

Other objects and advantages of my invention will be more readily understood by reference to the accompanying drawings, in 60 which—

Figure 1 is a side elevation and partial vertical section showing a complete burner in connection with a portion of a blast furnace stove, and also showing the manner of 65 connecting the burner with the gas main, this burner being shown assembled for operation with compressed air of comparatively high pressure;

Fig. 2 is an enlarged end elevation of the 70 burner shown in Fig. 1;

Fig. 3 is a vertical longitudinal section through the burner shown in Figs. 1 and 2;

Fig. 4 is a fragmentary end elevation showing the operating means for longitudinally moving the burner; 75

Fig. 5 is an end elevation of the burner shown in Figs. 1, 2 and 3, but assembled with an air admission means for operation with air introduced under comparatively 80 low pressure;

Fig. 6 is a vertical longitudinal section through a portion of the outer end of the burner, assembled as shown in Fig. 5;

Fig. 7 is an end elevation of the burner 85 shown in the preceding figures but assembled with a window-carrying member placed on the outer end of the main air inlet tube, so that all the air is drawn into the burner by the action of the gas itself; 90

Fig. 8 is a vertical longitudinal section through a portion of the outer end of the burner assembled as shown in Fig. 7.

The gas main 10 is provided in its upper surface with an aperture 11, and carries an 95 apertured platform 12, which, in turn, carries the apertured burner support 13, which is longitudinally movable through the in-

strumentality of the hand wheel 14, the pinion 15, and the rack 16. This mechanism is old and well known, and forms no part of my present invention.

6 The flange 17 of the gas burner is suitably bolted to the flange 18 of the burner support 13. The burner is provided with the main casing 19 which has the gas inlet 20, which, in turn, communicates with the gas 10 main 10 through the apertures of the platform 12 and the burner support 13, in the well-known manner. As is most clearly shown in Fig. 3, the casing 19, which is circular in cross-section, tapers toward its inner 15 end to the point of minimum diameter 21 beyond which there is a flare 22 of rapidly increasing diameter.

The outer end of the casing 19 has the circular aperture 23, which receives the main 20 air inlet tube 24, the bearing 25 of the tube 24 engaging the periphery of the aperture 23. The inner end of the main air inlet tube 24 is tapering, as clearly shown in Fig. 3, and its inner edge 26 is approximately in 25 the plane of the most restricted portion 21 of the casing 19.

The main air inlet tube 24 is provided with the bosses 27, through which pass the bolts 28, the inner ends of which are screwed 30 into the casing 19, and the outer ends of which are threaded and carry the nuts 29. A pair of the nuts 29 engage opposite surfaces of each of the bosses 27, thereby securely holding the air inlet tube 24 in position. It will be evident that by proper movement of the nuts 29 the main air inlet tube 24 may be moved inwardly or outwardly, as desired, on its bearing 25 within the aperture 23. The main air inlet tube 24 is provided with the air inlets 30, and the effective area of these inlets may be regulated by rotation of the ring valves 31, these ring valves being held in adjusted position by means of the screws 32. Just beyond and 45 inside of the air inlets 30 the main air inlet tube 24 has a restriction 33, of the shape of the well-known Venturi tube.

The outer end of the air inlet tube 24 has the inwardly-extending flange 34, to which 50 may be interchangeably attached the various parts which adapt the burner for use under varying conditions. In the assembly of the burner illustrated in Figs. 1 to 3, inclusive, the tapering auxiliary air inlet tube 35 extends into the main air inlet tube 24, and its inner end is located substantially in the plane of the restriction 33 of the main air inlet tube 24. The flange 36 of the auxiliary air inlet tube 35 engages the flange 34, and 55 is held in position by means of the bolts 37. The auxiliary air inlet tube 35 carries at its outer end the spider 38, which, in turn, supports the compressed air pipe 39 extending

into the auxiliary air inlet tube 35. The compressed air pipe 39 is provided with a nozzle 40 having a flaring end 41, which serves to direct the incoming compressed air or other fluid in a diverging stream which, when it reaches the inner end of the auxiliary air inlet tube 35, occupies the entire 70 cross-sectional area of the latter, and serves to draw air into the auxiliary air inlet tube 35 through its open outer end.

Continuous with the inner end of the casing 19 is the mixing chamber casing 42, within which is formed the mixing chamber 43. The casing 42 carries around its periphery the secondary air inlet frame 44, provided with the secondary air inlets 45, the effective area of which may be regulated by the ring valve 46. The inner edge of the secondary air inlet frame 44 is preferably provided with a packing ring 47, which, during operation of the burner, is brought into engagement with the circular frame 48 mounted on the stove or furnace 49. As clearly shown in Fig. 3, the inner end of the mixing chamber casing 42 is tapered so that an annular passage 50 is provided through which additional or secondary air is drawn 90 and mixed with the gas and air mixture which passes from the mixing chamber 43 into the stove or furnace 49.

In Figs. 5 and 6 all the parts of the burner which I have described are the same 95 as shown in Figs. 1 to 3, with the exception that the auxiliary air inlet tube 35 is removed and the tube 51 substituted therefor. This tube 51 has the flange 52 engaging the flange 34, and is held in position by means of the 100 bolts 37. The tube 51 may be connected with a suitable source of low pressure air such as comes from a fan blower.

In Figs. 7 and 8 the end closure 53 carrying a glass window 54 is substituted for 105 the tube 51 of Figs. 5 and 6, and the auxiliary air inlet pipe 35 of Figs. 1 to 3.

Having thus described the construction of the various parts which are used in my invention, the operation of the same may now 110 be readily understood:

When it is desired to mix a relatively large quantity of air with the gas and to utilize this air for the purpose of mixing relatively low pressure gas with it, the parts 115 of my burner are assembled as shown in Figs. 1 to 3, inclusive. Compressed air of relatively high pressure enters through the pipe 39, and by means of the nozzle 40 is directed in a diverging stream so that when 120 the latter reaches the inner end of the tube 35 the pressure of air is uniform throughout the entire cross-sectional area. The compressed air serves to draw in additional air through the open end of the auxiliary air 125 inlet tube 35. This body of air then passes

into the main air inlet tube 24 substantially in the plane of the venturi-like restriction 33, which serves to draw in still additional air. The rapid expansion of air which takes place just beyond the restriction 33 causes the air drawn in through the inlets 30 to be thoroughly mixed with the air coming from the tube 35. All of the air then moves with gradually increasing velocity through the tapering main air inlet tube 24, and on passage from the latter is mixed with the gas which surrounds the tube 24 and which has entered the casing through the gas inlet 20. It will be evident that the air as it leaves the inner end of the air inlet tube 24 has reached its maximum velocity, and thereby causes a strong inducing effect on the gas which is brought into intimate contact with the air by the taper of the casing 19. The rapid increase in diameter of the casing 19 in its portion 22 causes the gas and air to decrease in velocity and to be mixed with each other, the thorough mixing of the gas and air being completed as the mixture passes through the mixing chamber 43. If it is desired to add still additional air to the mixture, the ring valve 46 is opened to the desired extent, and as the gas and air mixture passes from the inner end of the mixing chamber 43 so-called "secondary" air is drawn through the annular passage 50 and is mixed in the stove or furnace 49 with the mixture coming from the mixing chamber 43. Combustion then takes place within the stove or furnace 49.

It will be evident that in the operation of the burner the amount of gas which is admitted may be regulated by longitudinal movement of the main air inlet tube 24, thus regulating the cross-sectional area of the annular gas passage formed between the main air inlet tube 24 and the tapering portion of the casing 19.

In many instances it is found satisfactory to force air into the burner under comparatively low pressure instead of using a relatively highly compressed air designed to be used in connection with the assembly of parts shown in Figs. 1 to 3. Under such circumstances the assembly of parts shown in Figs. 5 and 6 may be used, the air being introduced through the air pipe 51 under a few ounces of pressure. This air then entrains additional air drawn in through the air inlets 30 and the additional features of operation of the burner are as previously described.

If the conditions of operation are such that the gas itself exercises a sufficient inward action to mix with it the required amount of air, the assembly of parts shown in Figs. 7 and 8 is used. In such case the gas passing the inner end of the main air

inlet tube 24 at its maximum velocity draws air in through the air inlets 30, and the mixture passes through the mixing chamber 43, and, if desired, has secondary air mixed with it, in the manner previously described.

It will be evident to those skilled in the art that changes can be made in the detailed construction of the various parts which I have described without departing from the spirit and scope of my invention, as defined in the appended claims.

What I claim is:

1. In a gas burner, the combination of a casing having a gas inlet therefor, and an air inlet tube projecting into said casing and having a tapered inner end, said air tube having a venturi-like restriction outside of its tapered inner end.

2. In a gas burner, the combination of a casing having a gas inlet therefor, and an air inlet tube extending into said casing and having a tapered inner end and having its outer end projecting outside of said casing, said air inlet tube being provided with an air inlet outside of said casing and having a venturi-like restriction between said inlet and the tapered inner end of said tube.

3. In a gas burner, the combination of a casing having a gas inlet therefor, a main air inlet tube extending into said casing and provided with a venturi-like restriction, and an auxiliary air tube extending into the end of said main air inlet tube and having its inner end terminating substantially in the plane of said restriction.

4. In a gas burner, the combination of a casing having a gas inlet therefor, a main air inlet tube extending into said casing and provided with a venturi-like restriction, an auxiliary air tube extending into the end of said main air inlet tube and having its inner end terminating substantially in the plane of said restriction, and means for introducing fluid under pressure into the outer end of said auxiliary air inlet tube.

5. In a gas burner, the combination of a casing having a gas inlet therefor, a main air inlet tube extending into said casing and having a tapered inner end, a venturi-like restriction in said main air inlet tube outside of the tapered portion of said tube, a tapered auxiliary air inlet tube extending into the outer end of said main air inlet tube and with its inner end terminating substantially in the plane of said restriction, and a pipe extending into the outer end of said auxiliary air inlet tube and adapted to introduce into the latter fluid under pressure.

6. In a gas burner, the combination of a casing having a gas inlet therefor, a main air inlet tube extending into said casing and having a tapered inner end, a venturi-like

restriction in said main air inlet tube, a plurality of air inlets around the periphery of the outer end of said main air inlet tube, a tapered auxiliary air inlet tube extending 5 into said main air inlet tube and having its inner end terminating substantially in the plane of said restriction, and means for introducing a fluid under pressure into the outer end of said auxiliary air inlet tube.

10 7. In a gas burner, the combination of a

casing having a gas inlet therefor, an air inlet tube extending into said casing, and a plurality of air-controlling devices adapted to be selectively applied to the outer end of said air inlet tube, whereby the introduction 15 of air into said air inlet tube may be varied.

In witness whereof, I hereunto subscribe my name this 21st day of December, A. D., 1916.

HEINRICH J. FREYN.
